(57) **CLAIM**

The ornamental design for a wash basin, as shown and described.

DESCRIPTION

FIG. 1 is a front perspective view of a wash basin showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines in FIGS. 1-7 represent portions of the wash basin that form no part of the claimed design.
